CONTROLLING MEANS AND ACTUATING
MEANS THEREFOR

**Earnest J. Dillman, Detroit, Mich., assignor to
Detroit Lubricator Company, Detroit, Mich., a
corporation of Michigan**

Application July 3, 1941, Serial No. 400,939

27 Claims. (Cl. 200—138)

This invention relates generally to new and useful improvements in controlling means and actuating means therefor and which among other uses is particularly adapted for use to operate switches such as the fan and limit switches employed in heating systems.

One object of this invention is to provide a novel means for actuating a controlling means.

Another object is to provide a readily accessible means for adjusting the actuating means.

Another object is to provide a structure in which the controlling means is easily removable as an independent unit.

Another object is to provide the actuating means with a means for indicating the operation of the actuating means.

Another object is to provide an actuating means in which the controlling means is held in its actuated position subsequent to its actuation.

Another object is to provide means for overtravel of the actuating means.

Another object is to provide in a fan and limit control, means for interrelating the fan adjustment to the limit adjustment to insure closure of the fan switch prior to opening of the limit switch.

Another object is to provide means for limiting the maximum temperature at which the actuating means may be set by the operator for opening of the limit switch.

Another object is to provide a novel snap acting switch means.

Other objects will be apparent from a reading of the specification and the appended claims.

The invention consists of the improved construction of and combination of parts to be more fully described hereinafter and the novelty of which will be particularly pointed out and distinctly claimed.

In the accompanying drawings, to be taken as a part of this specification, there is fully and clearly illustrated a preferred embodiment of the invention in which drawings:

Figure 1 is a view in side elevation with the cover removed of a fan and limit switch mechanism embodying invention;

Fig. 2 is a view in front elevation with the cover removed of the mechanism of Fig. 1;

Fig. 3 is a view taken substantially along the line 3—3 of Fig. 1;

Fig. 4 is a view taken substantially along the line 4—4 of Fig. 2;

Fig. 5 is an exploded view of certain of the parts of the switch actuating mechanism;

Fig. 6 is a top plan view of the switch unit with the cover removed;

Fig. 7 is a view taken substantially along the line 7—7 of Fig. 6;

Fig. 8 is a view taken substantially along the line 8—8 of Fig. 6, and

Fig. 9 is a top plan view of the actuating cam for the switch unit.

Referring to the drawings by characters of reference, the numeral 1 designates generally a fan and limit switch mechanism having a housing 2, a hollow tubular supporting member 3 and a helical bimetallic actuating element 4. A mounting flange 4^a which is securely fastened to the wall of a furnace bonnet or the wall defining a heated space to be controlled has an aperture therethrough aligned with an aperture through the bonnet wall. The supporting member 1 extends through these apertures so that the bimetallic element 4 is positioned within the bonnet or space and the housing 2 is positioned externally of the bonnet or space. A set screw 4^b acts to lock the member 3 in position subsequent to proper insertion of the member 3 into the flange 4^a. The housing 2 is preferably U-shaped and has a rear wall 5, a top wall 6 and a bottom wall 7. A U-shaped cover member 8 having a front wall 9 and end walls 10 and 11 cooperates with the housing 2 to form a completely enclosed hollow casting for the switch units and the switch actuating mechanism to be described hereinafter. A bracket member 12 is secured at its opposite end portions to the extending or front edge portions of the walls 6 and 7 as by screws 13 and acts to hold the walls 6 and 7 in relative fixed space relation. A stub screw 14 is secured, as by riveting, to the member 12 and is positioned substantially midway between the walls 6 and 7 and extends through an aperture in the cover member front wall 9. A cap nut 15 rotatably secured to the wall 9 has screw-threaded connection with the screw 14 for holding the cover member 8 in its cooperative relation with the housing 2. One end of the bimetallic element 4 is secured as by means of a screw to a tab 16 which extends longitudinally outward from the supporting member 3 and the other end of the element is secured as by means of a screw to a flattened end portion 17 of a rod 18 which extends longitudinally of and beyond the end portion of the supporting member 3 having the tab 16. The tab 16 has an inturned portion 18^a extending through the longitudinal center line or axis of the member 3 and has an aperture therethrough in which the rod 18 is journaled. The other end portion of

the member 3 is rigidly secured to the rear wall 5 of the housing 2 as by means of four equally spaced tabs 19 which are peened to the wall 5. The rod 18 extends through an aperture 20 in rear wall 5 concentric with the supporting member 3 and terminates adjacent, but spaced from bracket member 12.

A switch unit supporting bracket 21 having its opposite end portions riveted to the walls 6 and 7 extends substantially parallel to but spaced from the wall 5. The bracket 21 has an aperture therethrough aligned with the aperture 20, through the rear wall 5, in which is secured a bearing member 22. The rod 18 extends through and is journaled for rotational movement in the member 22. The bracket 21 has adjacent the wall 6 a pair of offset lip portions forming slide rails 23, 24 spaced substantially parallel to the plane of the bracket 21 and positioned on the bracket 21 front surface 25 which faces the wall 9, the rails being positioned on each side of the bearing member 22 and substantially equidistant therefrom and the outer edge surfaces of the bracket 21. A pair of offset lip portions forming slide rails 26, 27 are carried by the bracket 21 adjacent the wall 7 and are disposed in facing relationship to the rails 23 and 24 and in a similar position with respect to the bearing member 22. A first switch unit generally designated 28 and having a bottom casing portion 29 and a casing cover 30 is positioned against the front surface 25 and wedge shaped ears 31 extending outward from the opposite end walls or surfaces 31^a, 31^b of the casing portion 29 are positioned intermediate the rails 23 and 26 and cooperate therewith to hold the switch unit against the surface 25. When the cover member 8 is removed, the switch unit 28 may be slid through the open end wall 10 along the surface 25 until a recess in an edge portion 32 of the unit 28 perpendicular to the end surfaces 31^a and 31^b engages the bearing member 22 as a stop. The edge portion of the bracket 21 adjacent the wall 10 has a downturned lip portion 33 extending toward the wall 5 in which is threaded a screw 34 having a large head that engages an edge portion 35 of the unit 28 opposite to the portion 32 to hold the unit 28 against the member 22 and the ears within the rails 23 and 26. A second switch unit 36 similar to the unit 28 has a bottom casing portion 37, a casing cover 38, wedge shaped ears 39, an edge portion 40 engageable with the bearing member 22, and an edge portion 41 engaged by a screw 42 having a large head and screw threaded to a downturned lip portion 43 of the bracket 21 extending toward the wall 5 adjacent the wall 11.

Referring to Figs. 6-9, wherein the switch unit 28 is shown in detail, the bottom casing portion 29 carries a U-shaped bracket 50 adjacent the end wall 31^a and held to the top surface of the portion 29 as by screws 52. Knife edge slots 53 in the facing surfaces of the parallel portions of the bracket 50 receive the end portions of a reacting means 54 such as a leaf spring. The free length of the spring 54 is greater than the distance between the slots 53 so that the spring 54 is held in a bowed position. The spring 54 may be flexed to either of its bowed positions by a bell crank lever 55 which has a straight plate-like rectangular lever arm or member 56 which may be made of "Bakelite" or other insulating material and an L-shaped metallic member 57. The member 57 is of the same width as the spring 54 and one arm thereof which extends parallel

with a portion of the spring 54, has oppositely extending lips or ears which are rebent about the spring 54 adjacent one end portion thereof to secure the lever 55 to one face of the spring 54. A rivet 58 secures one end of the member 56 to the other arm of the member 57 so that as the extending end of the member 56 is moved laterally relative to the switch unit 28 and longitudinally of the spring 54, the spring 54 is flexed through center from one bowed position to another bowed position. As the lever member or arm 56 is moved toward the left, facing Fig. 8, it fulcrums on the spring 54 tending to stress the spring into an S-curve which raises the mid-portion of the spring 54 toward and ultimately through center, i. e. the straight line joining the spring ends. The casing bottom portion 29 and cover 30 have protruding abutments 58^a which are positioned adjacent the end portions of the spring 54 and on both sides thereof so that should the lever 55 be excessively moved, the end portions of the spring 54 will not "jump" out of the slots 53. During normal operation of the spring 54, the abutments 58^a have no function. A switch 58^b comprises a current conducting switch blade 59 which has one end secured to the casing portion 29 adjacent the end wall or surface 31^b and the wall 35, and extends longitudinally of the portion 29 and also is offset toward the wall 32. The blade 59 has at its other end portion an end slot which receives the transversely extending spring 54 at a point substantially two-thirds of the distance between the connection of the lever 55 to the spring 54 and the other end portion of the spring 54. A contact member 60 is carried by the blade 59 adjacent the slot and cooperates with a fixed contact member 61 carried by a current conducting member 62 which is held rigid with the casing 29 and extends substantially transverse to the blade 59. Upon movement of the bell crank lever 55 in a counterclockwise direction (see Fig. 8), the spring 54 will be moved to its bowed upward position and the blade 59 will be moved upward with a snap action thereby causing the contact members 60 and 61 to engage to complete an electric circuit. As the bell crank lever 55 is moved clockwise, the spring 54 will be moved to its bowed downward position and the blade 59 will be moved downward with a snap action thereby to part the contact members 60 and 61 and open the electric circuit. The transverse member 62 has a portion 63 which extends externally of the casing portion 29 and carries a connecting screw 63^a for conveniently connecting one lead wire of the circuit to be controlled to the fixed contact member 62. A T-shaped member 64 has a portion 64^a extending externally of the casing portion 29 which has a connecting screw 64^b for conveniently connecting the other lead wire of the circuit to be controlled. One of the oppositely extending portions of the T-shaped member 64 underlies and is in electrical contact with the secured end of the blade 59 so that the lead wire which is connected to the screw 64^b is electrically connected to the movable upwardly facing contact member 60. The casing cover 30 conforms in external contour to the casing bottom portion 29 and has a recessed portion which receives and encloses the parts carried by the bottom portion 29 to protect them from accidental contact with foreign substances. The bottom portion 29 has a supporting post 65 which extends upward and through an aperture 75 in the cover 30. A stub shaft 66 is carried by

the post 65 and extends upward therefrom to form a pivotal support for a U-shaped cam member 67, to be described more in detail hereinafter. The second switch unit 36 is constructed similarly to switch unit 28 and has a bell crank lever 68, a switch (not shown), terminal screws 70, 71 for connection to an electric circuit, a stub shaft 72, and a U-shaped cam member 73.

Fig. 5 shows the adjustable mechanism for actuating the cam members 67 and 73. The numeral 74 designates a cylindrical post or sleeve member having an outwardly extending peripheral flange 75 at its lower end portion and having flattened diametrically opposed wall portions 76. A helical coil spring 77 surrounds the sleeve member 74 and has one end portion seating against the flange 75 and has its other end portion abutting a washer or annular plate member 78 which is positioned on and concentric with the member 74. The inner periphery of the member 78 is circular and of substantially the same diameter as the member 74. A second annular plate member 79 is positioned on and concentric with the member 74 and has one surface in contact with the annular member 78. The inner contour of the member 79 is not a true circle but has chord-like portions 80 which conform to the flattened portions 76 so that the second member 79 is held against rotational movement relative to the member 74. A third annular member 81 having an upwardly offset annular central portion 82 and having a fan shaped segment 83 extending outward from and offset upwardly from its periphery, is positioned on and concentric with the cylindrical member 74, with the outer portion of the member 81 against the upper surface of the second member 79. The contour of the inner periphery of the member 81 is circular so that it may be rotated relative to the member 74. A fourth annular member 84 has an offset downwardly annular central portion 85 which engages the upwardly offset portion 82 and has a fan shaped segment 86, similar in size and shape to the segment 83, offset upwardly from its periphery so that it overlies the segment 83. A fifth annular member 87, identical with the second annular member 79, has its lower surface in contact with the outer portion of the member 84 and has chord-like portions 88 conforming to the flattened portions 76 so that the fifth member 87 is held against rotational movement relative to the member 74. A sixth annular member 89 similar to the third and fourth members 81 and 84 has an offset upwardly annular central portion 90 and an offset downwardly fan-like segment 91 at its periphery. The contour of the inner periphery of the member 89 like that of the members 81 and 84 is circular so that the member 89 may be rotated relative to the cylindrical member 74. The outer portion of the member 89 engages the upper surface of the fifth member 87. A seventh annular member 92 has an offset downwardly central annular portion 93 which engages the offset upwardly portion 90 and has an offset downwardly fan-like segment 94 which overlies the segment 91. The contour of the inner periphery of the member 92 is circular so that the member 92 may be rotated relative to the cylindrical member 74. The member 92 has at its outer periphery a downturned lug or ear 94^a which is engageable with an edge portion of the segments 83 and/or 86 to limit relative movement between the segments 83, 86 and 91, 94. An eighth an-

nular member 95 identical with the second and fifth annular members 79 and 87 has its lower surface engaging the outer portion of the member 92 and has chord-like portions 96 conforming to the flattened portions 76 so that the eighth member 95 is held against rotational movement relative to the member 74. The cylindrical member 74 has a central aperture 97 extending longitudinally therethrough and of a reduced diameter relative to the normal diameter of the rod 18. At the upper end portion of the member 74 opposite to the flange 75, there is an annular protuberance 98 which is concentric with the aperture 97 and is received within a central aperture 98 of a disk member 99 so that the lower surface of the member 99 can seat against the upper end surface of the cylindrical member 74. The disk member 99 is held in position as by the peening of the annular protuberance 98 and acts upon engagement of its lower surface with the upper surface of the eighth member 95 to hold the member 95 against movement in an upward direction. The force exerted by the spring 77 acts to frictionally hold all of the eight annular members 78, 79, 81, 84, 87, 89, 92 and 95 in tight frictional engagement so that rotation of the cylindrical member 74 will cause a corresponding rotation of the annular members 81 and 84, and 89 and 92 which are manually rotatable relative to the cylindrical member 74 for adjustment thereof. The adjustable mechanism generally designated 100 for convenience, comprises all of the elements designated by the numerals 74-99 each inclusive.

The end portion of the rod 18 which is positioned intermediate the bearing member 22 and the bracket member 12, is of reduced diameter for insertion into the aperture 97 of the mechanism 100. Subsequent to assembly, the mechanism 100 is secured rigid to the rod 18 as by solder which is received in a space 100^a formed between the inner periphery of the annular protuberance 98 and the reduced diameter portion of the rod 18. The segment 83 has a downwardly protruding abutment 101 which comprises a stub-shaft bearing 102 secured to the segment 83 as by riveting and having a tubular roller portion 103 rotatable about the bearing 102 and held thereon by a head portion 104. The segment 86 has a protruding abutment 105 similar to the abutment 101 comprising a stub shaft bearing 106, and a tubular roller portion 107 held on the bearing 106 by a head portion 108. The abutment 105 extends through an arcuate slot 109 in the segment 83 and the segment 86 has an arcuate slot 109^a receiving the riveted end of the stub shaft bearing 102 so that it does not interfere with manual relative movement of the members 81 and 84. The segments 91 and 94 are similarly arranged to the segments 83 and 86 with arcuate slots 110 and 111 respectively, the abutments 112 and 113 respectively, have roller portions 114, 115 and stub bearings 116, 117. The segments 83, 86, 91 and 94 have upstanding tabs 118, 119, 120 and 121 respectively, which extend beyond the upper surface of the disk member 99 and have respectively inwardly extending radial pointers 122, 123, 124 and 125 which cooperate with an indicia plate 126 adjustably secured as by a screw 127 to the upper surface of the disk member 99 to indicate the temperature at which the switch units 28 and 36 are actuated. The bracket member 12 has a perpendicularly extending finger or pointer 128 which co-

operates with the indicia plate 126 to indicate the temperature of the bimetallic element 4. To enable a person to see the temperature indicated by the pointer 128 with the cover member 8 in place, the cover member 8 has an aperture through the portion of the wall 9 which overlies the pointer 128 and which aperture is closed by a transparent pane 129.

A stop plate 130 is adjustably secured to the front surface of the indicia plate 126 and held by a screw 131 and has a portion 132 which lies in the path of movement of the tab 121 to limit the maximum temperature at which the member 92 may be set to actuate the switch unit 36. An arrow 133 which may be engraved in the front surface of the stop plate 130 cooperates with the indicia plate 126 to indicate the maximum temperature at which the plate 130 is set.

The generally U-shaped cam members 67 and 73 are in the form of rockable levers, the member 67 being shown in detail in Fig. 9. Projecting from the base of lever 67 are spaced and opposed arms or cams 134, 135 which diverge outwardly from the base. The inner face of cam 134 has a cam surface 136 from which there extends at an angle but in continuation thereof a curved cam holding surface 137. The inner face of cam 135 which faces or is opposed to the face of cam 134 has a cam surface 138 substantially parallel to surface 136. Extending from and in continuation of surface 138 but at an angle thereto there is a curved cam holding surface 139. The lever 67 has an arm or ear 140 projecting longitudinally from its base adjacent the arm 135. Through the ear 140 there is an hour-glass type slot 141 which receives the switch operating arm 56. The members or levers 67 and 73 are mirror copies of each other and therefore the exponent "a" applied to the reference characters designating the parts of lever 67 will designate like parts of the lever 73. The abutment members or posts 101 and 105, carried respectively by the segments 83 and 86 which form part of the oscillatable operating means for switch unit 28, travel in an arc concentric with shaft 18. The curvature of the holding surfaces 137 and 139 conforms to the arc inscribed by the radially outermost surfaces of the abutment members 101 and 105. The post or fulcrum 66 of lever 67 is positioned mid-way between the cams 134 and 135 and such that when lever 67 is rocked counterclockwise, facing Figs. 3 and 9, the holding surface 139 will be substantially concentric with shaft 18 and lie substantially parallel to the path of travel of abutment members 101 and 105. The holding surface 137 is eccentric to surface 139 and so positioned that on clockwise rotation of lever 67, it will be movable into a position substantially concentric with shaft 18 and lie substantially parallel to the path of travel of abutment members 101 and 105. The cam surfaces 136, 138 are, upon rocking of lever 67, alternately movable into the arc or path of travel of the abutment members 101 and 105 respectively. As the parts are positioned in Fig. 3, clockwise rotation of shaft 18 has just moved abutment member 105 into engagement with cam surface 138. Continued clockwise rotation of the shaft 18 will cause the abutment 105 to cam or rock the lever 67 counterclockwise about the shaft 66 against the force of bowed spring 54. When lever 67 has been rocked sufficiently to snap the spring 54 through center, the lever 67 will have continued movement by the reaction of spring 54 which will position the holding surface 139

substantially in a space position corresponding to the arc described by the abutment members 101 and 105. Further, clockwise rotation of the shaft 18 will cause the abutment member 105, and, if sufficient rotation is had, the abutment member 101, to move along the holding surface 139 and hold the lever 67 in this position. The segment slot 109 acts to limit relative movement of the members 81 and 84 so that the maximum distance between the abutment members 101 and 105 is always less than the distance between the cam surfaces 136 and 138 as described. Upon counterclockwise rotation of the shaft 18, the abutment members 101 and 105 are rotated toward the cam surface 136 which was positioned in the path of movement of the member 101 when the lever 67 was moved counterclockwise by the engagement of the abutment member 105 with the cam surface 138 and by the action of spring 54. Continued counterclockwise rotation of the shaft 18 causes the abutment member 101 to engage surface 136 and rotate the lever 67 about its shaft 66 against the force of spring 54. When the spring 54 has been moved through center, it will react on lever 67 to continue the lever movement to position the holding surface 137 concentric with the arc traced by the abutment members 101 and 105. Further counterclockwise movement of abutment members 101 and 105 will now carry them along the holding surface 137, thus locking the switch unit 28 in actuated position.

The switch unit 36 is so mounted on the bracket 21 that the cam member 73, pivotally carried by the stub shaft 72, is engaged and rotated by the abutment 113 upon clockwise rotation of the shaft or rod 18 when the pointer 125 passes a position in alignment with the pointer 128. Likewise, upon counterclockwise rotation of the shaft 18 the abutment 112 will engage and rotate the cam member 73 when the pointer 124 passes a position aligned with the pointer 128. The indicia on the indicia plate 126 which cooperates with the pointers 122 and 123 is spaced about the plate 126, and the switch unit 28 is positioned on the bracket 21 to hold the stub shaft 66 so that upon clockwise rotation of the shaft 18 the abutment 105 will rotate the cam member 67 when the pointers 123 and 128 indicate the same temperature. Upon counterclockwise rotation of the shaft 18 the abutment 101 likewise will rotate the cam member 67 when the pointers 122 and 128 indicate the same temperature. In assembling the switch 1 it is necessary merely to place the mechanism 100 only approximately in its correct cooperative relation with the shaft 18 before rigidly soldering them together. Later the temperature of the element 4 may be ascertained and the plate 126 rotated relative to the disk member 99 until the pointer 128 indicates the temperature of the element 4 and the screw 127 tightened. The temperatures indicated by the pointers 122, 123, 124 and 125 will be the temperatures at which the element 4 will actuate the switch units 28 and 36. With this type of calibration, it is unnecessary to disturb the relatively rigid connections through which the force necessary to actuate the switch is transmitted from the element 4. There being no force transmitted through the plate 126 during normal operation of the switch 1, the screw 127 need only be sufficiently tight to prevent any vibrational or gravitational force from causing the plate 126 to slip relative to the disk member 99 of the mechanism 100. Should the switch 1 lose its

calibration for some reason, it is necessary merely to place a thermometer adjacent the element 4, and then loosen the screw 127 and rotate the indicia plate 126 until the pointer 128 indicates the same temperature as is indicated by the thermometer. The pointers 122, 123, 124 and 125 will then require readjustment to the correct readings on the indicia plate 126 at which it is desired to have the switch units 28 and 36 actuated.

The bracket member 12 has spaced inturned ears 142 and 143 which are engaged by a radially extending lug 144 integral with the indicia plate 126 to prevent or limit undue rotation of the shaft 18 upon an abnormal temperature of the element 4. The lug 144 engages the ear 142 upon a decrease of temperature of the element 4 to about -25° F. and engages the ear 143 at a temperature of about 425° F. which temperatures are normally never reached by the element 4. The ears 142 and 143 are so positioned that at least one of the abutments 101, 105 is always in correct cooperative position with the lever or cam member 67 and that at least one of the abutments 112, 113 is always in correct cooperative position with the cam member 73.

The operation of the mechanism 1 is as follows: The parts as shown in the drawings are in a position such that the switch 58^b is in open circuit position and the switch (not shown) positioned within the unit 36 is in closed circuit position. As the temperature of the bimetallic element 4 increases, the rod 18 will be rotated clockwise (see Fig. 3) by the element 4 and the abutment 105 carried by the oscillatable operating means will engage the cam surface portion 138 and will rotate the cam member 67 counterclockwise about the stub shaft 66 thereby moving the bell crank member 55 to bow the spring 54 from the downwardly bowed position shown in Fig. 8 to an upwardly bowed position. This movement causes the switch 58^b to close the circuit controlled thereby and the holding surface 139 to align itself with the arc of movement of the abutments 101 and 105. With the 93° F. setting of the annular member 84 as shown by the pointer 123, the switch 58^b will be closed when the temperature of the element 4 is about 93° F. Any further heating of the element 4 will cause the abutment 105 and/or abutment 101 to ride along the holding surface 139 without altering the position of the cam member 67 and/or the operation of the switch 58^b.

As the temperature of the element 4 increases to about 130° F., the abutment 112 also carried by the oscillatable operating means will engage the cam surface 136^a and will rotate the cam member 73 counterclockwise about the stub shaft 72 causing the bell crank lever 68 to bow the leaf spring (not shown) within the unit 36 causing the contact members therein (not shown) to open the circuit between the screws 70 and 71. Continued temperature increase of the element 4 will cause the abutment 112 and/or abutment 113 to move along the holding surface 137^a, which like the holding surface 137, will then coincide with the arc traced by the outside of the abutments 112 and 113 as the shaft 18 is rotated.

As the temperature of the element 4 decreases to about 120° F., the abutment 113 will engage the cam surface 138^a rotating the cam member 73 clockwise about the stub shaft 72 into the position shown in Fig. 3 to move the bell crank lever 68 thereby bowing the spring (not shown) within the unit 36 and closing the circuit between the

screws 70 and 71. A decrease in temperature below 120° F., causes the abutment 113 and/or abutment 112 to move along the cam surface portion 139^a without change in the operation of the unit 36. Upon a decrease in temperature of the element 4 to about 68° F., the abutment 101 will engage the cam surface 136 and rotate the cam member 67 clockwise about the stub shaft 66. This clockwise rotation of member 67 will move the bell crank lever 56 thereby bowing the spring 54 into the position shown in Fig. 8 and causing the switch 58^b to open the circuit between the screws 63^a and 64^b. Should the temperature of the element 4 decrease below 68° F., the abutment 101 and/or abutment 105 will move along the holding surface 137 without change in operation of the switch unit 28.

The annular temperature setting members 81, 84, 89 and 92 may be manually rotated about the cylindrical member 74 and may be moved relative to each other by the upstanding tabs 118, 119, 120 and 121, respectively, the pointers 122, 123, 124 and 125 respectively, cooperating to indicate the setting of the annular members with which they form a part. The downturned lug or ear 94^a of the annular member 92 acts to engage the edge portion of the segment 83 and/or segment 86 to prevent the members 81 and 84 from being adjusted so that the switch 58^b is closed or opened less than 25° F. below the closing or opening of the switch (not shown) within the switch unit 36. The arcuate slots 109 and 110 are so arranged that the abutments 105 and 113 which extend respectively therethrough engage the end portions thereof to limit relative movement of the annular members 81 and 84, and 89 and 92 respectively, to allow a minimum differential setting requiring about 18° F. temperature change to actuate the respective switch units 28 and 36. The slots 109 and 110 also act to limit the maximum differential setting to about 100° F. In this manner, when the switch unit 28 is used as a blower switch and the switch unit 36 is used as a limit switch in a blower limit combination for a heating unit such as a furnace, there is no possibility that an inexperienced operator may adjust the limit switch to open and thereby close down the heating unit prior to energization of the fan or blower which circulates the heated medium to the space to be heated. Also in like manner, there is no possibility that the blower switch will deenergize the fan or blower prior to reclosing of the limit switch unit 36 subsequent to opening thereof due to an undesired high temperature having been reached in the heating unit.

The annular members 81, 84, 89 and 92 are held in set position subsequent to manual adjustment by the frictional force exerted therebetween and by the annular members 79, 87 and 95. As the members 79, 87 and 95 are held against rotation relative to the cylindrical member 74 and member 74 is held rigid with the shaft 18, the members 81, 84, 89 and 92 will be rotated in accordance with the shaft 18 except when manually moved for adjustment.

It may now be seen that this invention provides a new and useful interrelation of controlling means and actuating means therefore which is simple of manufacture, simple of operation and easily repaired in the event one of the parts becomes defective. This invention also provides a new and useful means for calibrating a temperature actuated switch without altering the path by which the force for actuating the switch is

transferred thereto from the temperature actuated means.

What is claimed and is desired to be secured by Letters Patent of the United States is:

1. In an apparatus of the character described, a rockable lever having opposed cams, each cam having a cam surface, an oscillatable operating means having abutment means engageable on one stroke with one of said cam surfaces to rock said lever in one direction and engageable on the other stroke with the other of said cam surfaces to rock said lever in the opposite direction, a bowed leaf spring movable through center, a lever arm projecting from a face of said spring and operatively connected to said lever, said spring being operable on movement through center by said lever to complete each rocking stroke of said lever, and control means operable by said spring upon its movement through center.

2. In an apparatus of the character described, a rockable lever having opposed cams, each cam having a cam surface and a holding surface, an oscillatable operating means having abutment means engageable on one stroke with one of said cam surfaces to rock said lever in one direction and engageable on the other stroke with the other of said cam surfaces to rock said lever in the opposite direction, reacting means operable by said lever and acting during movement of said lever to complete each rocking stroke of said lever, and control means operable by said reacting means, said lever alternately positioning its holding surfaces substantially parallel to the path of movement of and for lateral engagement with said abutment means.

3. In an apparatus of the character described, a rockable lever having opposed cams, each cam having a cam surface, an oscillatable operating means having an abutment member engageable on one stroke with one of said cam surfaces to rock said lever in one direction, said operating means having a second abutment member engageable on the other stroke with the other of said cam surfaces to rock said lever in the opposite direction, reacting means operable by said lever and acting during movement of said lever to complete each rocking stroke of said lever, control means operable by said reacting means, and means to adjust the distance between said abutment members to determine the differential of operation of said control means.

4. A control device comprising a supporting member, a rotatable shaft carried by said member, a housing having a base and a cover and secured to said supporting member, control means mounted in said housing on said base, an operating arm projecting from said control means and through said cover, a rockable lever journaled exteriorly on said cover and having an aperture receiving said operating arm, spaced arms projecting from said lever and each having a cam surface, said surfaces being in opposed facing relation, an abutment member on said shaft and engageable with one of said cam surfaces to rock said lever in one direction upon rotation of said shaft in one direction, and a second abutment member on said shaft and engageable upon rotation of said shaft in the opposite direction with the other of said cam surfaces to rock said lever in the opposite direction.

5. In an apparatus of the character described, a supporting member, a rotatable shaft carried by said member, a controlling means carried by said member and having an actuating portion, an

actuating member pivotally secured to said supporting member and operatively connected to said actuating portion, said actuating member being operable upon pivotal movement to move said controlling means, a pair of plate-like members frictionally held to said shaft and having abutting surface portions, one of said plate-like members having an arcuate aperture therethrough concentric with said shaft, the other of said plate-like members having a protruding abutment extending through said arcuate aperture and beyond the surface of said one plate-like member opposite to its abutting surface portion, a protruding abutment carried by said one plate-like member and extending from said one plate-like member opposite surface, the wall of said arcuate aperture cooperating with said second-named protruding abutment to limit relative movement of said plate-like members, said protruding abutments being operable upon rotation of said shaft to engage said actuating member thereto to rotate said actuating member and move said controlling means.

6. In an apparatus of the character described, a supporting member, a rotatable shaft journaled in said member, a pin member carried by said supporting member and having its longitudinal axis substantially parallel to said shaft, a cam member pivotally carried by said pin member and having a pair of cam surfaces, a first plate member carried by said shaft and frictionally held thereto for rotation therewith, a first peg carried by said plate member and engageable with one of said cam surfaces to move said cam member toward one position upon rotation of said shaft in one direction, a second plate member carried by said shaft and frictionally held thereto for rotation therewith, a second peg carried by said second plate member and engageable with the other of said cam surfaces to move said cam member toward a second position upon rotation of said shaft in a second direction, said one surface having a surface portion spaced radially from said shaft upon movement of said cam member to said one position so that upon continued movement of said shaft in said one direction said first peg will maintain said cam member in said one position, said other surface having a surface portion spaced radially from said shaft upon movement of said cam member to said second position so that upon continued movement of said shaft in said second direction said second peg will maintain said cam member in said second position, and means actuated upon movement of said cam member.

7. In an apparatus of the character described, a supporting member, a rotatable shaft carried by said member, a controlling means carried by said member and having an actuating portion, a U-shaped lever member having laterally spaced arms and having an aperture therein for receiving said actuating portion, said lever member being operable upon pivotal movement to actuate said controlling means, said arms having cam surfaces on their inwardly facing edge portions, a pair of plate members frictionally held to said shaft and having abutting surface portions, one of said plate members having an aperture therethrough, a protruding abutment on the other of said plate members and extending through said aperture and beyond said one plate member, a protruding abutment carried by said one plate member and extending away from said other plate member, the wall of said aperture cooperating with said first-named abutment to limit

relative movement of said plate members, said protruding abutments being operable upon oscillation of said shaft to engage alternately said cam surfaces thereby to rotate said lever member and move said controlling means.

8. In a device of the character described, an adjustable operating means comprising a cylindrical member, a radially extending outwardly projecting flange on said member and adjacent one end portion thereof, said cylindrical member having a longitudinal recess extending along an external surface thereof, a helical coil spring concentric with said cylindrical member and having one end portion abutting said flange, a first annular member having a portion extending into said recess and held thereby for rotation with said cylindrical member, a pair of plate-like members having a central aperture therethrough for receiving said cylindrical member and rotatable relative to said cylindrical member and positioned against first annular member, a second annular member having a portion extending into said recess and held thereby for rotation with said cylindrical member and positioned against said pair of members, and means limiting said second annular member against movement toward the other end portion of said cylindrical member, said spring acting to urge said annular members and said plate-like members into tight frictional engagement.

9. In a device of the character described, an adjustable operating means comprising a cylindrical member, a radially extending outwardly projecting flange on said member and adjacent one end portion thereof, said cylindrical member having a longitudinal recess extending along an external surface thereof, a helical coil spring concentric with said cylindrical member and having one end portion abutting said flange, a first annular member having a portion extending into said recess and held thereby for rotation with said cylindrical member, a pair of plate-like members having a central aperture therethrough for receiving said cylindrical member and rotatable relative to said cylindrical member and positioned against said first annular member, a second annular member having a portion extending into said recess and held thereby for rotation with said cylindrical member and positioned against said pair of members, a second pair of plate-like members having a central aperture therethrough for receiving said cylindrical member and rotatable relative to said cylindrical member and positioned against said second annular member, a third annular member having a portion extending into said recess and held thereby for rotation with said cylindrical member and positioned against said second pair of members, means carried by one of said pair of members and engageable with the other of said pair of members for limiting relative rotation therebetween, and means limiting said third annular member against movement toward the other end portion of said cylindrical member, said spring acting to urge said annular members and said plate-like members into tight frictional engagement.

10. In an apparatus of the character described, a cylindrical member having a recess in its side wall and having an outwardly extending radial flange adjacent one end portion, a helical coil spring concentric with said cylindrical member and having one end portion abutting said flange, a first annular member positioned on said cylindrical member and having a portion fitting

into said recess and held thereby for rotation with said cylindrical member, a pair of plate-like members each having a central aperture therethrough and each having a segment extending from a peripheral portion thereof, said pair of members being positioned against said first annular member with said cylindrical member extending through said central aperture, a second annular member positioned on said cylindrical member and having a portion fitting into said recess and held thereby for rotation with said cylindrical member, a disk member secured to the end portion of said cylindrical member opposite to said one end portion and having a radius substantially equal to the radius of said segment-like portions, said disk member acting to limit movement of said pair of members and said annular members by said spring so that said first and said second annular members will be tightly held in engagement with said pair of members, grip members secured to said segment-like portions and extending therefrom beyond said disk member for manual movement of said pair of members relative to said cylindrical member.

11. In an apparatus of the character described, a cylindrical member having a recess in its side wall and having an outwardly extending radial flange adjacent one end portion, a helical coil spring concentric with said cylindrical member and having one end portion abutting said flange, a first annular member positioned on said cylindrical member and having a portion fitting into said recess and held thereby for rotation with said cylindrical member, a pair of plate-like members each having a central aperture therethrough and each having a segment-like portion extending from a peripheral portion thereof, said pair of members being positioned against said first annular member with said cylindrical member extending through said central aperture, a second annular member positioned on said cylindrical member and having a portion fitting into said recess and held thereby for rotation with said cylindrical member, a disk member secured to the end portion of said cylindrical member opposite to said one end portion and having a radius substantially equal to the radius of said segment-like portions, said disk member acting to limit movement of said pair of members and said annular members by said spring so that said first and said second annular members will be tightly held in engagement with said pair of members, grip members secured to said segment-like portions and extending therefrom beyond said disk member for manual movement of said pair of members relative to said cylindrical member, a calibrated plate-like member adjustably secured to said disk member on the surface thereof away from said pair of members, and pointers carried by said grip members and cooperable with said calibrated member to indicate the setting of said pair of members relative to said cylindrical member.

12. In an apparatus of the character described, a cylindrical member having a recess in its side wall and having an outwardly extending radial flange adjacent one end portion, a helical coil spring concentric with said cylindrical member and having one end portion abutting said flange, a first annular member positioned on said cylindrical member and having a portion fitting into said recess and held thereby for rotation with said cylindrical member, a pair of plate-like members each having a central aperture therethrough and each having a segment-like portion

extending from a peripheral portion thereof, said pair of members being positioned against said first annular member with said cylindrical member extending through said central aperture, a second annular member positioned on said cylindrical member and having a portion fitting into said recess and held thereby for rotation with said cylindrical member, a disk member secured to the end portion of said cylindrical member opposite to one end portion and having a radius substantially equal to the radius of said segment-like portions, said disk member acting to limit movement of said pair of members and said annular members by said spring so that said first and said second annular members will be tightly held in engagement with said pair of members, one of said segment-like portions having a slot therethrough, a pin carried by the other of said segment-like portions and projecting through said slot, a second pin carried by said one segment-like portion, and means actuated by said pin members upon rotation of said cylindrical member.

13. In an apparatus of the character described, a casing having a rear wall and spaced parallel side walls extending substantially perpendicular to said rear wall and extending from the front surface thereof, said rear wall having an aperture therethrough, a rotatable shaft extending through said aperture and into said casing, a plate spacer member having its opposite edge portions secured to said side walls and extending substantially parallel to and spaced from the inner surface of said rear wall, a bearing member carried by said spacer member and extending away from said rear wall, said shaft being journaled in said bearing member, a pair of clamping rails positioned one adjacent each side wall and carried by said spaced member on the front surface thereof away from said rear wall, said spacer member having a downturned ear extending toward said rear wall and positioned adjacent one end portion, a switch housing having a pair of extending flanges and having a switch actuating portion, said flanges being received and guided by said pair of rails, means carried by said ear for removably holding said housing against said bearing member, and means carried by said shaft and overlying said switch housing for actuation of said switch portion upon movement of said shaft.

14. In an apparatus of the character described, a U-shaped casing having a rear wall and a pair of substantially parallel spaced side walls extending from the front surface of said rear wall, a plate-like spacer member extending between said side walls and positioned adjacent to said rear wall, a reinforcing member extending between said parallel side walls and having its front surface adjacent the front edge portions of said parallel side walls, a bearing member carried by said spacer member and having its longitudinal axis substantially parallel to said parallel side walls, said rear wall having an aperture therethrough, a shaft journaled in said bearing member and having a rearwardly extending portion extending through said aperture and a forwardly extending portion, a first disk member rigidly secured to said shaft and positioned adjacent but spaced from the rear surface of said reinforcing member, a calibrated disk member positioned against said first disk member intermediate said first disk member and said reinforcing member, a pointer carried by said reinforcing member and cooperable with said cali-

brated disk member to indicate the position of said shaft, a switch member mounted on said spacer member intermediate said spacer member and said first disk member, means for actuating said switch member, and means frictionally held to said shaft and cooperable with said actuating means for actuation of said switch member upon rotation movement of said shaft.

15. In an apparatus of the character described, 10 a U-shaped casing having a rear wall and a pair of substantially parallel spaced side walls extending from the front surface of said rear wall, a plate-like spacer member extending between said side walls and positioned adjacent to and spaced from said rear wall, a reinforcing member extending between said parallel side walls and having its front surface adjacent the front edge portions of said parallel side walls, a bearing member carried by said spacer member and having its longitudinal axis substantially parallel to said parallel side walls, said rear wall having an aperture therethrough aligned with said bearing member, a shaft journaled in said bearing member and having a rearwardly extending portion extending through said aperture and a forwardly extending portion, a first disk member rigidly secured on said forwardly extending shaft portion and positioned adjacent the rear surface of said reinforcing member, a calibrated disk member positioned 20 against said first disk member intermediate said first disk member and said reinforcing member, a pointer carried by said reinforcing member and cooperable with said calibrated disk member to indicate the position of said shaft, a switch member carried by said spacer member intermediate said spacer member and said first disk member, means for actuating said switch member, means rotatably adjustable on said shaft and cooperable with said actuating means to actuate said switch member upon rotational movement of said shaft, means on said adjustable means and cooperable with said calibrated disk member for indicating the position of said shaft for actuating said actuating means, a finger portion carried by said reinforcing member and positioned adjacent the peripheral portion of said calibrated disk member, and means carried by said calibrated disk member and engageable with said finger portion for limiting movement of said shaft.

16. In an apparatus of the character described, 25 a U-shaped casing having a rear wall and a pair of substantially parallel spaced side walls extending from the front surface of said rear wall, a reinforcing member extending between said parallel side walls, said rear wall having an aperture therethrough, a bearing member aligned with said aperture and supported by said casing, a shaft extending through said aperture and journaled in said bearing member, a first disk member rigidly secured to said shaft and positioned adjacent but spaced from the rear surface of said reinforcing member, a calibrated disk member adjustably secured to the front face of said first disk member, a pointer on said reinforcing member and cooperable with said calibrated disk member to indicate the position of said shaft, a switch member positioned between said rear wall and said first disk member and having an actuating portion, operating means 30 adjustably mounted on said shaft, means for transmitting movement from said operating means to said switch actuating portion for actuation of said switch member upon rotational movement of said shaft, indicating means on said

operating means and cooperable with said calibrated disk for indicating the position of said shaft at which said operating means will actuate said actuating portion, a U-shaped cover member fitting said side and rear walls, and means carried by said reinforcing member for securing said cover member to said casing, said cover member having an aperture therethrough registering with said pointer for observation of said indicating means and of the pointer indicated position of said shaft from the exterior of said cover member.

17. In a device of the character described, a supporting member, a rotatable shaft carried by said member, a first snap acting switch carried by said member and having an actuating portion, a second snap acting switch carried by said member on the opposite side of said shaft from said first switch and having an actuating portion, a first supporting post positioned adjacent said first switch and extending substantially parallel to said shaft, a second supporting post positioned adjacent said second switch and extending substantially parallel to said shaft, a first lever member pivoted on said first post and operatively connected to and for actuating said first switch portion upon pivotal movement of said first lever member, a second lever member pivoted on said second post and operatively connected to and for actuating said second switch portion upon pivotal movement of said second lever member, a first pair of plate-like members each having an annular portion for receiving said shaft and each having a sector portion extending from one edge thereof, said sector portions being positioned in overlying relationship, one of said sector portions having an arcuate slot therethrough concentric with said shaft, the other of said sector portions having a first projecting pin extending through said arcuate slot and beyond said one sector portion, a second projecting pin extending from said one sector portion and away from said other sector portion, said pins being operable to engage alternately said first lever member upon oscillation of said shaft thereby to rotate said first lever member, a second pair of plate-like members each having an annular portion for receiving said shaft and each having a sector portion extending from one edge thereof, the second pair of sector portions being positioned in overlying close-adjacent relationship, one of said second pair of sector portions having an arcuate slot therethrough concentric with said shaft, the other of said second pair of sector portions having a first projecting pin extending through said second-named arcuate slot and beyond said one of said second sector portions, a second projecting pin carried by the other of said second pair of sector portions and extending away from said one of said second sector portions, said third-named and said fourth-named pins being operable to engage alternately said second lever member upon oscillation of said shaft thereby to rotate said second lever member, means frictionally holding said first pair and said second pair of plate-like members for rotation with said shaft, means carried by each of said plate-like members for independent movement thereof relative to said shaft, and means carried by one of said pairs of members and engageable with the other of said pairs of members to limit relative movement therebetween thereby to maintain the relative operation of said switches between predetermined limits.

18. A switch mechanism comprising a casing, a pair of spaced abutments, a leaf spring having a free length greater than the distance between said abutments and being held in either of two bowed positions therebetween, a flexible blade extending substantially perpendicularly to said spring and operatively connected thereto, switch means operable by said blade, a bell crank lever having one arm secured to said spring adjacent one end portion thereof and operable to move said spring to either of said bowed positions, a fulcrum pin carried by said casing, a lever member fulcrumed on said pin and having an aperture receiving the other arm of said lever, said lever member being operable upon rotation thereof about said fulcrum to move said lever thereby to move said spring from one to another of said bowed positions, and means rigid with said casing and operable to limit rotation of said lever member.

19. In a switch mechanism, a supporting member, a switch, a shaft carried by said supporting member, force transmitting means adjustable on said shaft and operable to transmit a force for actuation of said switch, indicating means carried by said force means, a pointer fixed relative to said supporting member, said indicating means having a predetermined position relative to said pointer at the position of operation of said switch by said force means, an indicia carrying means independent of the transmission of force by said force means from said shaft to said switch, the indicia of said carrying means being cooperable with said indicating means and said pointer, said carrying means being adjustable relative to said indicating means and said pointer to calibrate the indicated operation of said switch by said shaft.

20. A switch mechanism comprising a casing having base and cover members, a U-shaped supporting member secured to said base member and having arms extending parallel to the base of said base member, said arms each having on its inner face a longitudinal bearing groove, a leaf spring having its ends seating in said grooves and held in bowed position between said arms, switch means in said casing and operable by said spring, said base and cover members having opposed abutments adjacent said arms and operable to hold said spring against bowing movement out of said grooves, and means extending into said casing for moving said spring through center into oppositely bowed positions.

21. A switch mechanism comprising a casing having base and cover members, a pair of spaced abutments in said casing and secured to said base member, a leaf spring held in bowed position between said abutments, switch means operable by said spring and secured in said casing to said base member, said cover member having a plurality of apertures therethrough, a lever secured to said spring and operable to move said spring through center into oppositely bowed positions, said lever extending through one of said apertures, a bearing pin secured to said base member and extending through another of said apertures, and a lever member journaled on said pin external of said casing and operable to move said lever to actuate said switch means.

22. A switch mechanism comprising a casing, a pair of spaced abutments, a leaf spring having a free length greater than the distance between said abutments and being held in either of two bowed positions therebetween, a flexible blade

extending substantially perpendicularly to said spring and operatively connected thereto, switch means operable by said blade, a bell crank lever having one arm secured to said spring adjacent one end portion thereof and operable to move said spring to either of said bowed positions, a fulcrum pin carried by said casing, a lever member fulcrumed on said pin and having operative connection with the other arm of said lever, and means to oscillate said lever member to actuate said switch means.

23. In an apparatus of the character described, a control means, a lever having a fulcrum and having a pair of opposed spaced cams positioned one on each side of said fulcrum, a rotatable operating member having a pair of abutment members engageable with said cams and spaced apart a distance less than the distance between said cams, one of said abutment members being engageable with one of said cams upon rotation of said operating member in one direction to initiate movement of said lever in one direction, the other of said abutment members being engageable with the other of said cams upon rotation of said operating member in the opposite direction to initiate movement of said lever in the opposite direction, spring means movable through center and operatively connected to said control means, a lever arm projecting from said spring means and oscillatable by said lever to position said spring means on the opposite sides of its center, said spring means being operable by reaction upon movement through center to complete each initiated movement of said lever.

24. In a switch mechanism, a supporting member having an aperture therethrough, a bearing member extending from said supporting member and secured in said aperture, a shaft journaled in said bearing member, a pair of spaced clamping rails projecting from said supporting member, switch supporting means having opposite securing portions slidable into clamped relation between said rails and said supporting member, switch mechanism carried by said switch supporting means, means on said shaft for actuating said switch mechanism, and a clamping member having a flange locking said switch supporting means against movement out of said clamped relation.

25. In a switch mechanism, a supporting member having an aperture therethrough, a bearing

member extending from said supporting member and secured in said aperture, a shaft journaled in said bearing member, a pair of spaced clamping rails projecting from said supporting member, switch supporting means having opposite securing portions slidable into clamped relation between said rails and said supporting member, switch supporting means having an edge recess to receive a side portion of said bearing member, switch mechanism carried by said switch supporting means, means on said shaft for actuating said switch mechanism, and a screw member threaded into said supporting member and having a head engaging the edge of said supporting means opposite to said edge recess to hold said supporting means against said bearing member.

26. In a switch mechanism, a supporting member, a switch, a shaft carried by said supporting member, an operating member frictionally held to said shaft for adjustment thereabout and operable to actuate said switch, a plate member rigid with said shaft, an indicia plate having indicia and journaled on said shaft, means for clamping said plate in adjusted position to said plate member, an indicator on said operating member and cooperable with said indicia, and an indicator rigid with said supporting member and cooperable with said indicia, said indicia plate being adjustable relative to said indicators to calibrate the indicated operation of said switch by said shaft.

27. In a switch mechanism, a supporting member, a switch, a shaft carried by said supporting member, an operating member frictionally held to said shaft for adjustment thereabout and operable to actuate said switch, a plate member rigid with said shaft, an indicia plate having indicia and journaled on said shaft, means for clamping said plate in adjusted position to said plate member, an indicator on said operating member and cooperable with said indicia, an indicator rigid with said supporting member and cooperable with said indicia, said indicia plate being adjustable relative to said indicators to calibrate the indicated operation of said switch by said shaft, a stop plate journaled on said shaft and cooperable with said operating member to limit adjustment of said operating member, and means to hold said stop plate in adjusted position.

EARNEST J. DILLMAN.

CERTIFICATE OF CORRECTION.

Patent No. 2,303,028.

November 24, 1942.

EARNEST J. DILLMAN.

It is hereby certified that error appears in the printed specification of the above numbered patent requiring correction as follows: Page 2, second column, line 57, for "member 62" read --member 61--; page 6, second column, line 22, claim 5, for "thereto" read --thereby--; page 8, second column, line 8, claim 14, for "rotation" read --rotational--; and that the said Letters Patent should be read with this correction therein that the same may conform to the record of the case in the Patent Office.

Signed and sealed this 23rd day of February, A. D. 1943.

(Seal)

Henry Van Arsdale,
Acting Commissioner of Patents.
